UNITED STATES PATENT OFFICE.

WILLIAM H. BOLDUC, OF CLIFTON HEIGHTS, PENNSYLVANIA.

DRAWING-ROLL.

1,018,867.

Specification of Letters Patent. Patented Feb. 27, 1912.

Application filed August 2, 1910. Serial No. 575,099.

To all whom it may concern:

Be it known that I, WILLIAM H. BOLDUC, a citizen of the United States, residing in Clifton Heights, county of Delaware, and State of Pennsylvania, have invented certain new and useful Improvements in Drawing-Rolls, of which the following is a specification.

This invention relates to an improvement 10 in top rolls of drawing frames and has special reference to the so-called French system of drawing. By this system, wool is drawn in a dry state through a machine which prepares the wool for the spinning frame. The 15 top rolls in the French system of drawing are held against fluted rolls, by means of heavily weighted levers. Much difficulty has been experienced in this class of work in obtaining a covering for the top rolls of a 20 satisfactory nature.

The principal object of the present invention is to provide a top drawing roll, which is efficient in character, simple in structure and comparatively inexpensive to manufac- 25 ture.

A further object of the present invention is to provide a top drawing roll so constructed that when worn the parts may be readily replaced without material loss of time.

30 A still further object of the invention is to provide a top drawing roll working surface which serves to keep down static electricity and which may be readily peeled from off the said roll and a new covering applied.

35 A still further object of the present invention is to provide a top drawing roll so constructed as to reduce the number of weights ordinarily used upon a drawing frame.

40 Other objects of the invention relate to general details of construction and arrangement of parts as will hereinafter more fully appear.

The invention consists of the improve- 45 ments hereinafter described and finally claimed.

The nature, characteristic features and scope of the invention will be more fully understood from the following description 50 taken with the accompanying drawing forming part hereof and in which:

Figure 1, is a view partly in elevation and partly in central section of a top drawing roll embodying the invention, and Fig. 2, is 55 an end elevational view of the same.

In the drawings the drawing roll comprises a shaft 1, having formed integral therewith comparatively narrow enlarged cores 2. Built up upon the cores 2, are a series of concentric layers of material forming 60 an outer covering and a foundation. The outer covering consists of very thin parchment paper 3. In practice best results have been obtained by using for this covering 3, what is called in the trade animal parchment. This parchment is strong, tough and durable and provides a smooth even surface and serves to reduce static electricity which obviously is advantageous. The foundation of the drawing roll is composed of soft pliable rubber 4, interposed between layers of fabric 5, and 6. The material 5, may be fulled into a thick soft pliable feltlike material in contradistinction from being a woven cloth. Commercially, felt is particularly adapted for this purpose, although I do not wish to limit myself to the use thereof. In practice the layer of rubber is considerably thicker than either the canvas or felt, and the felt is thicker than the canvas. The purpose of the canvas 6, which is glued or otherwise united to the core 2, is to provide a suitable surface to accept the layer of rubber 4. The rubber and canvas layers may be readily united together by 75 cementing, gluing or the like. Likewise, the rubber 4, felt 5, and parchment 3, may be glued or otherwise united together. In this connection, it may be remarked that the parchment 3, forming the outer covering of 80 the roll may be easily and readily peeled from off the felt 5. This is important, in that, as the parchment wears away, a new covering may be expeditiously applied in view of the fact that the old parchment easily peels off from the felt. If the parchment 3, were applied to the rubber 4, the parchment would not peel off and the roll would have to be placed in a lathe and trued up. By the use of soft pliable rubber in the foundation for the covering 3, it may be said that 85 such rubber provides a cushion-like portion for the felt 5. Aside, from this fact, the soft rubber layer 4, in combination with the felt 5, serves to reduce the number of weights needed to about one third of the number of weights now in use from machines of the character indicated. This is true because of the yielding like qualities of the roll's surface, the fluted rolls do not require many 90 100 105 110

weights for keeping them in contact with the said drawing roll.

What I claim is:

1. A drawing roll provided with an outer covering comprising a single layer of parchment paper and a foundation composed of rubber, interposed between a layer of thick soft pliable feltlike material and a layer of canvas the various elements being united to each other and to the roll.
2. A drawing roll provided with an outer covering comprising a single layer of parchment paper and a foundation composed of rubber, interposed between a layer of thick soft pliable feltlike material and a layer of canvas the various elements being united to each other and to the roll.

ment paper and a foundation composed of soft pliable rubber interposed between a layer of fabric fulled into a thick soft pliable material and a layer of woven cloth the elements being united to each other and to the roll. 15

In testimony whereof I have hereunto signed my name.

WILLIAM H. BOLDUC.
